FRANK E. ANDRES, OF ALHAMBRA, CALIFORNIA.

GASIFYING APPARATUS.

1,300,170.

Specification of Letters Patent. Patented Apr. 8, 1919.

Application filed June 12, 1918. Serial No. 239,517.

To all whom it may concern:

Be it known that I, DANIEL H. JEFFERSON, a subject of the King of Great Britain, residing at Los Angeles, in the county of Los Angeles and State of California, have invented new and useful Improvements in Gasifying Apparatus, of which the following is a specification.

This invention relates to gasifying apparatus and it has for its object to provide apparatus of the character stated whereby liquids which are susceptible of being gasified may be readily converted into gases as required for use. My improved apparatus is particularly useful in fumigating work, such as the fumigation of fruit trees and the like, where it is desired to subject the trees to the action of a germicidal gas to the end that scale and other parasitic growths on the tree may be destroyed; for this purpose a liquefied product, hydro-cyanic acid, generated by the reaction between sodium cyanide, sulfuric acid and water, or other liquid having the required qualities, may be employed, and such liquid or liquefied gas is usually brought to the field of use in suitable tanks or containers from which it may be transferred to my apparatus, for gasifying and application to the tree, the preferred practice being to cover the tree to be treated with a tent or the like, and then introduce the gasified liquid thereunder as by means of a suitable nozzle device.

In accordance with my invention a suitable receptacle or tank having a preferably measuring discharge pumping means is provided, and such pumping means may be arranged to deliver liquid into a receiver where air under pressure is applied thereto and which receiver is preferably in the form of a helix of tubing the helix being shown as having its axis horizontally disposed, a discharge nozzle device adapted for insertion beneath a tent being connected to the helix. Furthermore, a vent pipe may be provided at the top of the receptacle to permit the entrance or discharge of air in compensation for the varying liquid level and such vent pipe is preferably bent downwardly and extended along a connection pipe between the coil and the nozzle device where it terminates, so that escaping fumes or gases are delivered at a point remote from the operator's position and the possibility of danger to the operator removed. The air supply means

may comprise an air pump or compressor, and the entire apparatus may be mounted upon a suitable base and so rendered portable to facilitate the work of fumigation. The tank or receptacle may be provided with a filling orifice through which liquid or liquefied gas may be placed therein, as by connecting a supply pipe leading from the shipping tank therewith; by extending such supply pipe to the bottom of the shipping tank and admitting fluid pressure to the shipping tank a convenient method of transferring the liquefied gas may be used.

The invention has for a further object the provision of improved gasifying apparatus which will be superior in point of relative simplicity and inexpensiveness of construction and organization in connection with safety and convenience in use, positiveness in operation and freedom from liability to get out of order.

With the above and other objects in view, the invention consists in the novel and useful provision, formation, construction, combination, association and relative arrangement of parts, members and features, all as hereinafter described, shown in the drawing, and finally pointed out in claims.

In the drawing:

The figure is a side elevation, partly in section for clearness of illustration, of apparatus constructed and organized in accordance with the invention.

The several parts in the figure are designated by reference characters.

Referring with particularity to the drawing, in the embodiment of the invention therein shown 1 designates a tank or receptacle having an inlet orifice at 2 normally sealed by a removable threaded plug 3, but shown as connected by means of a supply pipe 4 with a liquid containing shipping tank 5. One end 4^a of the pipe 4 is connected to the tank 1 as by a rubber tube 4' fitted into the orifice 2 and the other end 4^b of the pipe 4 extends to a point near the bottom of the shipping tank 5. A valve 6 may be provided in the pipe 4 and a pressure supply pipe 7 provided with a control valve 8 is shown as connected with the top of the tank 5.

The tank 1 has an aperture 9 in its bottom wall 1' and a measuring pump cylinder 10 has its open top portion connected with the bottom wall 1' as at 10^a, such pump cylinder 110

terminating at its lower end in a head 10^b provided with a discharge duct 10^c in which a check valve 10^d is disposed, a seat 10^e being provided for such valve. A piston 11 is fitted into the pump cylinder 10 and such piston 11 has an inlet duct 11^a passing therethrough in which duct a check valve 11^b is provided. A piston rod 11^c is connected at its lower end to the piston 11 and extends therefrom through the tank passing out of the tank through a packing device 12 and terminating in a handle 13 at its upper end. Below the handle 13 and above the tank 1, the rod 11^c is provided with a slidable finger 15 adapted to contact with a collar 15^a secured to the rod 11^c. A vertical gage member 16 projects upwardly from the top of the tank 1 and parallel to the piston rod 11^c and such gage member 16 has a series of notches 16^a into any one of which the finger 15 may be positioned by rotating it on the rod 11^c. At the edge of the gage member opposite the notched edge a series of projecting pins 16^b are provided, each such pin being in registration with a notch 16^a. Several lengths of pins 16^b may be employed, so that long pins are arranged with short pins and pins of an intermediate length between them, whereby the correct setting of the finger 15 in one of the notches 16^a may be made in the dark, as by operator finding the position of the required notch by counting long pins from one end of the series and then the required short or intermediate pins.

A pipe 17 leads from the discharge duct 10^c to a hollow arm 18^a of a coupling member 18, a check valve 18^b being positioned in such arm, and a pipe 19 has one end connected to an opposite and preferably higher hollow arm 18^c of the coupling member 18, in which hollow arm 18^c a check valve 18^d is disposed. The other end of the pipe 19 is connected with the discharge duct 20 of an air pump cylinder 21 in which cylinder 21 a piston 21^a is arranged for reciprocation by means of a piston rod 22 having a handle 23. A check valve 24 is provided in the duct 20.

The coupling member 18 is preferably located at about the level of the top of the tank 1 and has a downwardly ranging hollow discharge arm to which the inlet of a receiver 25 is connected as at 25^a. The preferred form of receiver is a helix of tubing the convolutions 25^b of which are vertically disposed. At the discharge end, the receiver is connected by means of a discharge pipe 25^c, which may be integral therewith, to a nozzle device 26 which is preferably spaced a short distance from the remaining portions of the apparatus so that it may be inserted beneath a tent.

The discharge pipe 25^c is shown as bifurcated at its discharge end as at 25^d and a

discharge nozzle 26 of any suitable design is fitted to each of the arms constituting the bifurcated end 25^d.

The pump cylinder 10 rests upon a base 27 at its head 10^b and so supports the tank 1, and the lower end of the air pump cylinder 21 is secured to the base; at the top of the tank 1 a peripheral band 28 is provided and such band may pass about the air pump cylinder 21 near its upper end and so unite the tank and air pump cylinder. A handle 29 has one of its ends secured to the tank 1 near the packing device 12 and has its other end connected to the band 28 near the air pump thus providing means whereby the device may be readily transported from tree to tree as the work proceeds, the position of the handle providing for balance of the apparatus about the handle.

A vent pipe 30 is connected with the top of the tank 1 and extends downwardly therefrom to the plane of the discharge pipe which it parallels to the nozzle, so carrying fumes or vapors forced through the vent pipe in filling the apparatus to a point remote from the operator's position as the filling proceeds.

A liquid level indicating gage 31 having a dial 32 positioned at the top of the tank 1 is provided in the tank.

An illuminating means such as an electric light globe 32^a mounted upon the tank permits reading the liquid level gage and the metering gage constituted by the notched member 16, finger 15, and collar 15^a.

The operation, method of use and advantages of the invention will be readily understood from the foregoing disclosure, taken in connection with the accompanying drawing and the following statement:

The tank 1 may be filled by inserting the rubber tube 4' of the pipe 4 leading from the shipping tank into the orifice 2 and admitting suitable pressure medium to the shipping tank to force a supply of the contained liquid hydro-cyanic acid gas therefrom and into the tank 1. The valve 6 may be closed when the level gage 31 indicates that the desired quantity of liquid has been transferred to the tank 1, the rubber tube removed, and the cap 3 threaded into the orifice 2 to seal the tank 1. During the filling operation the gage 31 is watched from a distance by the operator to avoid any possibility of inhaling deadly fumes. The apparatus may now be carried to a tree which has been covered with a tent and the discharge nozzle device inserted beneath the tent. The cubic contents of the tent may be estimated, and as different sizes of trees support the tents so that various cubic contents are met with in carrying on fumigating work, a charge of the liquefied gas proportionate to the tent contents may be used, and the required charge is measured by feel-

ing along the pins 16^b and so locating the proper notch into which the finger 15 is caught by rotating the same about the rod 11^c, it being understood that the measuring 5 discharge pump piston 11 is at the bottom of its cylinder 10. The member 16 may be provided with indicia 16^a whereby the proper notch 16 to correspond to a given tent capacity may be indicated; an operator after familiarizing himself with the scale or indicia reading in terms of cubic contents of tent or of cylinder charge may properly position the finger 15 in the required notch by feeling and counting the 15 pins 16^b, and so locating the notch desired. As the piston 11 is moved upwardly by means of the handle 13 the collar 15^a on the piston rod strikes the finger 15 and so limits upward travel of the piston 11 with the 20 result that a definite charge of liquefied gas is inducted to the space in the cylinder 10 below the piston 11, the check valve 11^b permitting such induction to the lower portion of the cylinder through the duct 11^a. The 25 piston 11 is now forced downwardly through the handle 13 and rod 11^c to the lowermost limit of its travel and the measured charge is forced or transferred past the check valves 10^d and 18^b and through 30 the member 18 into the receiver, where it is subjected to the expelling action of a body of compressed air supplied by forcing the air pump piston 21^a downwardly by means of its operating handle 23 and rod 22. As 35 many strokes of the air pump piston may be made as are required to force the entire charge through the receiver, discharge pipe and nozzle device and so gasify the charge, the air being forced past the check valve 24, 40 through the pipe 19, past the check valve 18^d, through the member 18 and into the receiver.

Having thus disclosed my invention, I claim and desire to secure by Letters Patent:

45 1. In apparatus of the character disclosed, a receiving receptacle adapted to contain liquefied gas, means for discharging a predetermined charge of such liquefied gas therefrom; a receiver adapted to receive said charge, and pressure means for ejecting said charge from said receiver to gasify the same.

50 2. In apparatus of the character disclosed, a receiving receptacle adapted to contain liquefied gas, means for discharging a predetermined charge of such liquefied gas therefrom, a receiver adapted to receive said charge, and pressure means for ejecting said charge from said receiver to gasify the same; there being a nozzle device connected with 55 said receiver and through which said charge is ejected.

60 3. In apparatus of the character disclosed, a receiving receptacle adapted to contain liquefied gas, means for discharging a predetermined charge of such liquefied gas

therefrom, a receiver adapted to receive said charge, and pressure means for ejecting said charge from said receiver to gasify the same; said pressure means comprising an air compressor adapted to deliver a charge 70 of air behind the charge of liquefied gas in the receiver.

4. In apparatus of the character disclosed, a receiving receptacle adapted to contain liquefied gas, means for discharging a predetermined charge of such liquefied gas 75 therefrom, a receiver adapted to receive said charge, and pressure means for ejecting said charge from said receiver to gasify the same; said pressure means comprising an air compressor adapted to deliver a charge 80 of air behind the charge of liquefied gas in the receiver; there being a nozzle device connected with said receiver and through which the charge is ejected for application to an object to be fumigated.

5. In fumigating apparatus, a liquefied gas receiving receptacle, a discharge pump having communication with said receptacle, means for actuating said pump, a receiver, 90 means for measuring a charge of liquefied gas to be transferred by said pump to said receiver, an air compressor connected to said receiver, means to actuate said air compressor whereby a charge of air may be 95 placed in the receiver to expel the charge of liquefied gas, and a projecting nozzle connected to said receiver and through which the charge of liquefied gas is expelled to gasify the same.

6. In fumigating apparatus, a liquefied gas receiving receptacle, a discharge pump having communication with said receptacle, means for actuating said pump, a receiver, 100 means for measuring a charge of liquefied gas to be transferred by said pump to said receiver, an air compressor connected to said receiver, means to actuate said air compressor whereby a charge of air may be 105 placed in the receiver to expel the charge of liquefied gas, and a projecting nozzle connected to said receiver and through which the charge of liquefied gas is expelled to gasify the same; said measuring means comprising means for limiting the capacity 110 of the pump.

7. In fumigating apparatus, a liquefied gas receiving receptacle, a discharge pump having communication with said receptacle, means for actuating said pump, a receiver, 115 means for measuring a charge of liquefied gas to be transferred by said pump to said receiver, an air compressor connected to said receiver, means to actuate said air compressor whereby a charge of air may be 120 placed in the receiver to expel the charge of liquefied gas, and a projecting nozzle connected to said receiver and through which the charge of liquefied gas is expelled to gasify the same; said measuring means com- 125

prising means for limiting the capacity of the pump and said receiver comprising a helical tube.

8. In fumigating apparatus, a liquefied gas receiving receptacle, a discharge pump having communication with said receptacle, means for actuating said pump, a receiver, means for measuring a charge of liquefied gas to be transferred by said pump to said receiver, an air compressor connected to said receiver, means to actuate said air compressor whereby a charge of air may be placed in the receiver to expel the charge of liquefied gas, and a projecting nozzle con-

nected to said receiver and through which 15 the charge of liquefied gas is expelled to gasify the same; said measuring means comprising means for limiting the capacity of the pump and said receiver comprising a helical tube having vertically disposed convolutions.

In testimony whereof, I have signed my name to this specification in the presence of two subscribing witnesses.

DANIEL H. JEFFERSON.
